AUTOMATIC TENSION OR SLACK LINE TAKE-UP
FOR LIFEBOAT WINCHES AND THE LIKE

Joseph C. Patterson, Jr., Alexandria, Va.

Application December 12, 1952, Serial No. 325,735

7 Claims. (Cl. 254—187)

This invention relates to power transmissions and more particularly to a mechanism for transmitting torque in hoist equipment.

In hoisting and lowering boats from a ship the problem of slack cable is presented due to the fact that the waves can and do overhaul and recede from the boat, thereby varying the proportion of the load borne by the cable and often bringing about marked variations in the load borne at a given instant by separate bow and stern cables. Slack cable in hoisting or lowering life boats with personnel aboard is, of course, very dangerous since, when a wave recedes under slack cable conditions, acute angular disposition of the boat may result. Acute shocks also occur as the slack cable is taken up by the descending boat.

The foregoing problem has long been recognized and many types of automatic cable tensioning devices have been designed in order to solve it. However, their mechanisms were complicated and involved auxiliary motors and devices. Consequently they were very costly to build. On the other hand, less costly devices have proven to be unreliable and hence unsafe.

It is, therefore, an object of this invention to provide an automatic cable tensioning or slack line take-up which is safe and reliable in use and at the same time is far less costly than the more satisfactory prior art devices.

Other objects and advantages of this invention will be apparent from the following detailed description of a preferred embodiment thereof in conjunction with the annexed drawings, wherein:

Figure 1 is a general assembly view, largely in vertical section, showing the coacting relation of the various parts making up one half of the transmission between the power and the load; and

Fig. 2 is a fragmentary view in section taken along the line 2—2 of Figure 1.

Referring now to the drawings in greater detail, the assembly is comprised of a cable drum 10 to which one end of a hoist cable 11 is attached. The cable drum may be helically grooved on its external surface to accommodate cable wound thereon and it is assumed that cable guiding means and a drum brake may be associated with the drum 10 in accordance with prior art practice.

The drum 10 is keyed to a driving shaft 12 and to that shaft there is also keyed a driving gear 13. The shaft 12 is mounted in suitable bearings diagrammatically indicated at 14 and 15.

Meshing with the gear 13 is a pinion 16 which forms a part of the transmission of the present invention. The pinion 16 is connected by circumferentially arranged bolts or studs 17 to a housing 18 constituting one side or end of a constant torque spring motor. The other side or end of the spring motor is keyed at 19 (see Figure 2) to a shaft 20 to which power is applied. The shaft 20 has keyed thereto a gear 21 which meshes with a pinion 22 which in turn is keyed to a driving shaft 23 which is connected to a power source not shown such as an electric motor.

Referring now in greater detail to Figure 2 and to the parts of Figure 1 lying immediately to the left of the pinion 16, it will be observed that the housing 18 is mounted for rotation about the shaft 20 by means of a bearing 24 at one end and the bearing 25 of the pinion 16 at the other. The housing 18 defines, as an integral part, a clutch face 26 coaxial with the shaft 20 and, within the housing 18 to the left of the clutch face 26 there is located a ball bearing nut 27, in threaded engage-

2

ment with the shaft 20. The nut 27 has on its right side, as viewed in Figure 1, a clutch face registerable with the clutch face 26. Radial pins 28 extend from the nut and pass through longitudinally extending slots 29 in the housing 18. By this arrangement the nut 27 is permanently locked against rotation relative to the housing 18 although it is free to move longitudinally on the shaft 20 as a result of the screw action with that shaft. It is evident that such action will permit the clutch to be either engaged or disengaged. The parts 30 and 31 at opposite ends of the shaft 20 are merely bearings for the shaft which may be made according to the prior art and hence are diagrammatically shown.

Upon reference to Figure 2 it can be seen that the spring motor is comprised of a central spindle 32 keyed to the shaft 20 at 19, and eight circumferentially spaced spindles 33 mounted in the housing 18 and extend axially thereof. Around each of the spindles 33 there is wound a prestressed coil spring, one end of which is anchored to the spindle 33 and the other end of which is anchored to the spindle 32. It can be seen, therefore, that relative rotation between the shaft 20 and the housing 18 will cause the springs to be wound back and forth between their spindles 33 and the single spindle 32. This type of device is known as a Negator motor. It has been developed by the Negator Division of the Hunter Spring Company, of Lansdale, Pennsylvania, and is fully described in an article in Machine Design for January, 1951. The essence of this type of spring motor is that the torque transmitting properties between the central spindle, such as 32 here shown, and the outer spindles, such as 33 here shown, are constant irrespective of the magnitude of relative angular displacement between the shaft 20 and the housing 18. The springs themselves are so prestressed and preshaped that the torque exerted by the constant length X depicted in Figure 2 is constant irrespective of the amount of spring wound on the central spindle or one of the outer spindles. The reason for using a number of springs instead of one is to increase the over-all torque transmitting properties of the motor.

With the explanation, it is possible to describe the function of the hoist apparatus as a whole in such an operation as lifting a boat from the water onto a ship. In that case let it be assumed that the cable is connected to a boat but is not under load. Let it likewise be assumed that the water is still so that there is no relative movement between the boat and ship due to wave action. Under such circumstances, shaft 23 is driven in a hoist direction as indicated by the arrows in Figure 1. This causes the shaft 20 to turn in a counter-clockwise direction as viewed in Figure 2. Since the shaft 20 turns and since there is no load on the cable, the torque of shaft 20 is transmitted through the various springs to the spindles 33, from them to the housing 18 and from the housing 18 to the pinion 16 and from it to the gear 13, the shaft 12 and the drum 10. As long as there is no load on the cable the nut 27 will not move because the housing 18 will turn with the shaft 20. As soon as the load is taken by the cable, however, the springs of the spring motor 18 will no longer be able to transmit sufficient torque. The result will be that the housing 18 will be held against rotation by the load while the shaft 20 will continue to turn. This will result in winding the springs onto the spindle 32 and, because housing 18 is immobilized, will also result in movement of the nut 27 to the right of Figure 1 to a clutch engaging position. As soon as the clutch is engaged, the load will be moved for the clutch is so designed that it can transmit all of the torque necessary to lift the design load of the equipment.

Assume now that the load is moving upwardly and is momentarily overhauled by a wave. If that happens there is a tendency for the load to be reduced sharply with a resulting tendency to produce slack cable. On the other hand, the spring motor being fully wound, instantly accelerates the pinion 16 beyond the R. P. M. at which it is driven through the clutch 26—27 and takes out the slack, at the same time disengaging the nut 27 and so disengaging the clutch. This allows the boat to go down again as the wave recedes and as soon

as the load has again rewound the motor and re-engaged the clutch, hoisting recommences.

The value of the foregoing cycle can perhaps best be appreciated if one imagines a typical use of the apparatus of Figure 1 in which the apparatus of Figure 1 is duplicated, with one of the drums connected to the bow cable of a boat and the other connected to a stern cable. If a wave lifts the bow, the slack is immediately taken out of the cable as just described and, because the clutch is disengaged, the angular portion of the keel of the boat will never change except within small limits. In view of the fact that the running in and out of the nut 27 might, under some circumstances occur very rapidly, ring 34 is provided, connecting the outer ends of the radial pins 28. This ring has an external groove in it and, within the groove there is located an arm 35 pivoted at 36 and connected at 37 to a dashpot 38. The sole function of the dashpot 38 is to prevent excessively rapid clutch engagement with resulting shocks to the boat.

Since the whole assembly is encased in a casing 39, shown in broken lines in Figure 1, and since the assembly operates in an oil bath within said casing, the dashpot derives its operating fluid from the lubricants within the casing 39.

While the foregoing invention has been described with respect to but a single unit applied to but a single cable drum, it is to be understood that in hoisting a boat two units such as are shown in Figure 1 are used, one of them for each line to the boat, i. e., one to a bow line and one to a stern line. Both may and are ordinarily driven from a single shaft such as 23.

While from a theoretical point of view an ordinary nut will move as described on the threaded portion of the shaft 20, to prevent jamming it is highly desirable to use a ball bearing nut and screw arrangement of the type developed by Saginaw Steering Gear Division, General Motors Corporation, Saginaw, Michigan, and described in text book "Machine Design", First Edition (Revised) 7th Impression, by V. L. Maleev, published by International Textbook Co., Scranton, Pa.

What is claimed is:

1. A power transmission particularly suited to hoist apparatus, comprising a driving shaft, a rotatable part to which load is applied; a constant torque spring motor interconnecting said shaft and part, a normally open clutch also interconnecting said shaft and part, said motor being connected to said clutch to cause said part to move the clutch in an engaging direction in response to a power-load torque differential greater than the torque transmitting capacity of said motor.

2. A power transmission as claimed in claim 1, further comprising means acting to damp the engagement of said clutch.

3. A power transmission particularly suited to hoist apparatus, comprising a driving shaft, a rotatable part to which load is applied, a constant torque spring motor, a clutch having normally disengaged clutching elements, one side of said motor and one element of said clutch being fixed for rotation with said part, the other side of said motor being fixed to said shaft, the other element of said clutch being in threaded engagement with said shaft for axial movement therealong, and means restraining said other element of said clutch against rotation relative to said part whereby when the power-load torque differential exceeds the constant torque which the spring motor can transmit the threaded other element of the clutch and said shaft relatively rotate to move the clutch to closed position while energy is stored in the spring motor to disengage the clutch when the power-load

torque differential recedes to a value below the capacity of the spring motor.

4. A power transmission particularly suited to hoist apparatus comprising a shaft to which power is applied a coaxial part to which load is applied, a spring motor capable of exerting a substantially constant torque between its ends regardless of the degree to which it is wound, a clutch having normally disengaged clutching elements, one end of said motor and one element of said clutch being fixed to said part for rotation therewith about said shaft, the other end of said motor being keyed to said shaft, the other element of said clutch being threaded onto said shaft for axial movement therealong and being fixed against rotation relative to said part, whereby when the load on said part exceeds the torque transmitting capability of said motor said clutch is engaged by the relative rotation between said other clutch element and said shaft while energy is stored in the spring motor.

5. A power transmission particularly suited to hoist apparatus comprising a driving shaft, a rotatable part to which load is applied, means exerting a constant torque irrespective of the magnitude of relative angular displacement interconnecting said shaft and part, a normally open clutch also interconnecting said shaft and part, one element of said clutch being threaded onto said shaft through ball bearings for axial movement along the shaft, and means restraining said element against movement relative to said part whereby when the load on said part exceeds the torque transmitting capabilities of said torque exerting means the part and shaft relatively rotate and cause said element of said clutch to move to engaging position.

6. A power transmission particularly suited to hoist apparatus comprising a driving shaft, a rotatable part to which load is applied, a constant torque spring motor, a clutch having normally disengaged clutching elements, one side of said motor and one element of said clutch being fixed for rotation with said part, the other side of said motor being fixed to said shaft, the other element of said clutch being in ball bearing threaded engagement with said shaft for axial movement therealong, means restraining said other element of said clutch against rotation relative to said part and damping means acting through said restraining means to damp the shock of clutch engagement.

7. In hoist apparatus including a cable drum, a power supply, a shaft driven by the power supply, a part coaxial to said shaft, gearing connecting said part to said drum in driving relation, a spring motor capable of exerting a substantially constant torque between its ends regardless of the degree to which it is wound, said spring motor comprising a housing having a plurality of circumferentially spaced spindles thereon, a central spindle on said shaft and prestressed springs interconnecting said housing spindles and the spindle on said shaft, said housing being connected to said part and having an integral clutch face thereon coaxially surrounding said shaft, a ball bearing nut threaded on said shaft for axial movement therealong and having a clutch face thereon for engaging with the clutch face of said housing, longitudinal slots in said housing, and radial pins extending from said nut through said slots to restrain the nut and housing against relative rotation.
